Inventor:
Laurence H. Whitney,
by *Alvinda S. Lewis*
His Attorney.

UNITED STATES PATENT OFFICE.

LAURENCE H. WHITNEY, OF PITTSFIELD, MASSACHUSETTS, ASSIGNOR TO GENERAL ELECTRIC COMPANY, A CORPORATION OF NEW YORK.

LIGHTNING ARRESTER.

Application filed June 9, 1927. Serial No. 197,565.

My invention relates to an electrolytic cell. More particularly it relates to a cell of the type which is especially adapted for use as a lightning arrester, a rectifier or the like.

5 The cells of the foregoing type have been quite delicate in construction so that they have not been readily adaptable for use in rough service inasmuch as the elements are readily distorted either in service or due to 10 the process of assembling, packing or shipment.

The object of my invention is the provision of a cell of rigid and dependable construction so that its use need not be confined to 15 power stations and the like, but may be extended to include vehicular service such as electric railways and the like. The invention will be more readily understood by reference to the accompanying drawing, in 20 which Fig. 1 shows the elements of the cell assembled and in perspective; Fig. 2 shows the elements of the cell of Fig. 1 separated and in perspective; Fig. 3 indicates how the 25 cells are connected up in an electric railway car for example; Fig. 4 shows a modified form of the central element in the cell.

Referring more in detail to the drawing, it will be seen that the outer element 2 is preferably formed from a single piece of corrugated metal such as aluminum, preferably folded transverse its longitudinal axis, as indicated in Figs. 1 and 2. It will be seen that the inner element 3 is also formed from a single piece of metal such as aluminum, 35 which element is corrugated as indicated, the corrugations extending parallel to the longitudinal axis of the element. The outer element 2 is folded transverse its longitudinal axis to form a U-shaped electrode and is

40 provided with terminal strips 4 and 5, the upper sections of which strips are folded to form lugs 6 and 7 which lock with each other, thereby forming a bridge upon which the binding post 8 is secured. It will be seen that the element 2 is provided with longitudinal corrugations or ribs 9 and 10 which extend all the way from one end of the plate to the other. The corrugation 10 as shown 45 extends along the strips 4 and 5 and overlaps at the bridge where the strips are pressed together by the binding post 8. It will be seen that the corrugations extend also across the bottom bridge portion 11 of the element 2.

With a construction such as indicated, I obtain an outer element for an electrolytic cell 50 having stability and rigidity and which is free from any danger of being bent or crushed against the inner electrode 3 which electrode 3, as indicated, is located within the U portion of the outer electrode 2. Also, the inner 55 electrode cannot readily be bent or jarred into contact with element 2. The terminal of the inner electrode is formed from metal strips 12 and 12^a which extend beyond the active surface of the electrode and are brought together to form an arch with the terminals of the strips bound together by the binding post 13^a. The elements may be made preferably from aluminum plate, the thickness of the outer plate being preferably greater than the 60 thickness of the inner plate. The thickness of the material may be of the order of .040" to .060". In the type of cell shown in Fig. 1, the elements 2 and 3 are clamped to a porcelain plate 13 which serves also as the cap for 65 the jar which contains the elements 2 and 3 and the usual electrolyte. It will be observed that the porcelain element 13 is provided with channels 14 and 15 for receiving the terminal extensions. In these channels, 70 openings are provided through which the posts 8 and 13^a extend forming the terminals of the cell. The porcelain plate 13 is also provided with a groove for receiving the corrugation 10. In Fig. 4, I have shown a modified form of the inner electrode. In this 75 form, the terminal strip elements 16 and 17 are folded over for the purpose of strength of construction.

With the fragile type of construction heretofore used in connection with devices of the foregoing character, it has been a common source of trouble that the electrodes would become easily bent so that there would result uneven distribution of current which would 80 shorten the life of the cell. With the type of construction of my invention, this source of trouble is practically eliminated.

While I have shown my invention in connection with a specific form of construction, 85 I do not wish to be limited to such construction inasmuch as in view of the disclosure variations of the invention may be readily made without departing from the spirit thereof or from the scope of the claims contained 90 herein.

What I claim as new and desire to secure by Letters Patent of the United States, is:—

1. An electrode for an electrolytic cell in the form of a single piece of metal plate with 95

a reinforcing rib, and with a pair of terminal lugs one at each opposite end of the plate, the free ends of said lugs being brought together and bound to form a terminal and reinforcing arch for the electrode, said rib extending along said arch.

2. An electrode for an electrolytic cell in the form of a single piece of metal plate with a reinforcing rib, and with a pair of terminal lugs one at each opposite end of the plate, the free ends of said lugs being brought together and bound to form a terminal and reinforcing arch for the electrode, said rib extending along said arch, the ends of said rib meeting in said arch.

3. An electrode for an electrolytic cell in the form of a single piece of metal plate with a reinforcing rib, and with a pair of terminal lugs one at each opposite end of the plate, the free ends of said lugs being brought together and bound to form a terminal and reinforcing arch for the electrode, said rib extending along said arch, and a second rib on said plate for further strengthening the plate, said latter rib being confined to the plate region and excluding the lugs.

4. An electrode for an electrolytic cell in the form of a single piece of metal plate folded into a series of parallel corrugations

30 with a pair of terminal lugs one constituting an extension along one margin of the plate and the other constituting an extension along the opposite margin of the plate, the free ends of said lugs being brought together to form a reinforcing and terminal arch.

35 5. An electrolytic cell including an electrode in the form of a single piece of metal plate with a reinforcing rib, and with a pair of terminal lugs one at each opposite end of the plate, the free ends of said lugs being brought together and bound to form a terminal and reinforcing arch for the electrode, said rib extending along said arch, said cell including also an electrode in the form of a single piece of metal plate folded into a series of parallel corrugations with a pair of terminal lugs one constituting an extension along one margin of the plate and the other constituting an extension along the opposite margin of the plate, the free ends of said lugs being brought together to form a reinforcing and terminal arch, the latter electrode being located within the U region of the first electrode.

40 45 50 55 In witness whereof, I have hereunto set my hand this sixth day of June, 1927.

LAURENCE H. WHITNEY.
